DESIGN FOR A SLIPPER

Jack Macht, New York, N. Y.

Application March 26, 1941, Serial No. 99,895

Term of patent 3½ years

To all whom it may concern:

Be it known that I, Jack Macht, a citizen of the United States of America, residing in New York, county of New York, and State of New York, have invented a new, original, and ornamental Design for a Slipper, of which the following is a specification, reference being had to the accompanying drawing, forming part thereof.

Fig. 1 is a side elevational view of a slipper showing my new design.

Fig. 2 is a top plan view thereof.

I claim:

The ornamental design for a slipper, as shown.

JACK MACHT.
